(57) **CLAIM**

The ornamental design for an adjustable arm, as shown and
described.

DESCRIPTION

FIG. 1 is a perspective view of an adjustable arm showing
our new and ornamental design with a convex base;
FIG. 2 is front elevation view thereof;
FIG. 3 is a rear elevation view thereof;
FIG. 4 is a side elevation view thereof;
FIG. 5 is an opposite side elevation view thereof;
FIG. 6 is a top plan view thereof;
FIG. 7 is a bottom plan view thereof;
FIG. 8 is a perspective view of an adjustable arm showing
our new and ornamental design with a concave base;
FIG. 9 is front elevation view thereof;
FIG. 10 is a rear elevation view thereof;
FIG. 11 is a side elevation view thereof;
FIG. 12 is an opposite side elevation view thereof;
FIG. 13 is a top plan view thereof;
FIG. 14 is a bottom plan view thereof;
FIG. 15 is a perspective view of an adjustable arm showing
our new and ornamental design with a disc-shaped base
attached to a desk;
FIG. 16 is front elevation view thereof;
FIG. 17 is a rear elevation view thereof;
FIG. 18 is a side elevation view thereof;
FIG. 19 is an opposite side elevation view thereof;
(Continued)

FIG. 20 is a top plan view thereof; and,
 FIG. 21 is a bottom plan view thereof.
 The portions of the adjustable arm shown in broken lines in
 the figures attached hereto form no part of the claimed
 design and show the environment in which the adjustable
 arm comprising the claimed design is to be displayed.
